UNITED STATES PATENT OFFICE.

DAVID E. GRAY, HARRY R. BOALS, AND JAMES BAILEY, OF CORNING, NEW YORK,
ASSIGNORS TO CORNING GLASS WORKS, OF CORNING, NEW YORK, A CORPORATION
OF NEW YORK.

APPARATUS FOR SHAPING GLASS ARTICLES.

Application filed December 10, 1923. Serial No. 679,765.

To all whom it may concern:

Be it known that we, DAVID E. GRAY, HARRY R. BOALS, and JAMES BAILEY, all citizens of the United States of America, and all 5 residing at Corning, in the county of Steuben and State of New York, have jointly invented certain new and useful Improvements in Apparatus for Shaping Glass Articles, of which the following is a specification.

10 This invention relates to an apparatus for shaping glass, and it has particular relation to means for altering the shape of a desired portion or portions of articles which have been given a preliminary shape.

15 Among the objects of this invention are to provide means for holding the article while it is being operated on, means for heating the article to permit the shaping, means for bringing a shaping member into cooperative 20 relation with the article, coacting shaping means for imparting the configuration of the shaping member to the heated portion of the article, and a common means for controlling the heating means and the shaping means, 25 as will be hereinafter pointed out and claimed.

In the present application, by way of illustration, we have embodied our invention in an apparatus for forming lips on beakers, 30 although it is not limited to this purpose.

In the accompanying drawings forming part of this specification:—

Figure 1 is a side elevation, partly in section, of our machine, showing a burner 35 playing on the article to be treated;

Fig. 2 is a similar side elevation, but showing the shaping block raised to its functioning position, and the finger making the lip on a beaker, the burner arm being omitted 40 to more clearly show the remaining parts, and

Fig. 3 is a plan view of the machine in the position shown in Fig. 2.

Referring to the drawings, 1 is the base for 45 the machine on which is mounted the upright 2, which carries a bracket 3, adjustable in height by locking screws 4. A sleeve 5, rotatably mounted on the upright 2, has attached to it by the hinged joint 6, the operating lever 7. On the upper end of the upright 50 2 is the collar 8, held by the set screw 32.

Adjustably fixed to the sleeve 5 is the burner-carrying arm 9, the arm being angularly disposed, as shown, in respect to the

operating lever. The burners 10 and 11 carried by this arm are adjustable in direction, the one burner 11, being so directed in one angular position of the sleeve as to throw flame on the outer wall of the upper portion of the article held in the chuck 23 (to be 60 described later) while the other burner 10 is directed so that in the same position of the sleeve it throws flame on the inner surface of the article at the same point, but in a slightly downward direction (see 65 Fig. 1).

The burners 10 and 11 may be laterally adjusted by the thumb nuts 12 and 13, and may be also adjusted vertically and in inclination by the collars 14 and 15, carried 70 respectively by the downwardly projecting arms 16 and 17 from the burner arm 9.

The article to be treated is held in the chuck 23 by vacuum when the vacuum line 24 is opened at the valve 25. Running 75 through the base 1 and the end of the bracket 3 is the adjustable push-rod 18, which, on being depressed, tilts the lever 21. The outer end of the lever 21 is bifurcated, the arms thereof being pivoted to the lower 80 ends of the rods 22, the upper ends of which carry the shaping block 19, thereby lifting the block from its usual position in Fig. 1, up and adjacent to the upper end of the article, (see Fig. 2). The former 19 is ad- 85 justably connected to the rods 22 by the set screws 35.

The operating arm 7 carries on its outer end a telescopic extension 27 terminating in a handle 28. In the telescopic extension pivoted at 31, is the upper end of the finger 26, which acts as a wiper and may be of any desired shape or size, and is normally held at right angles to the arm, by the spring 33. The operating arm 7 is normally held elevated on its pivot 6 by a flange 30 on the bracket 3, but may be lowered when over 90 the chuck, the flange 30 being cut away at 34 to permit this.

The article 29 to be treated having been 105 put in the chuck 23, is held thereby vacuum when the valve 25 is opened. With the parts in the position shown in Fig. 1, burners 10 and 11 will play on and heat a portion on the edge of the article to the desired temperature. The operator then swings the operating lever 7 angularly over the cut away portion 34 of the flange 30, and then de- 110

presses the lever. The first movement moves the burner-carrying arm 9 away from the article, and places the finger 26 thereover, and the latter movement depresses the push-rod 18 to lift the shaping block 19 to a position adjacent the heated surface of the article, and inserts the finger 26 within the article. The operator then pulls the handle 28 and the finger is brought into contact with the 10 heated zone of the article at a point adjacent to the shaping block 19, and pushes or wipes the glass into the shaping block with a pressure determined by the spring 33, shaping a portion of the article into a lip or other 15 desired configuration determined by the shape of the shaping block and finger.

The above operations finish the article to the desired shape and it is then only necessary to unload the machine, and replace the 20 finished article by a new article to be treated. To accomplish this, the handle 28 is returned to its original position, which allows the spring 33 to bring the finger 26 to its vertical position. On raising the lever 7 by the 25 handle 28, pressure is removed from the push-rod 18, and the shaping block 19 drops down over the chuck 23, out of operating position on the bracket 20. Lever 7, on being raised as stated above, out of the cut-away 30 portion 34 of the flange 30, can be moved laterally in either direction so that neither burners nor lever 7 will be directly over the chuck. In this position a new article can be inserted, and on moving the lever 7 laterally 35 the burners are brought to play on this article, starting the cycle of operations over again.

While the particular embodiment of our invention disclosed herein is adapted for lip- 40 ping beakers, we desire to have it understood that our invention is susceptible of many other uses within the scope of the following 45 claims.

Having thus described our invention, what we claim as new and desire to secure by Letters Patent is:—

1. A glass shaping machine comprising, in combination, ware retaining means, means for heating the ware, a shape defining means, 50 a wiper, and means for moving the shape defining means and the wiper in respect to the ware retaining means and of each other.

2. A glass shaping machine comprising, in combination, ware retaining means, means for heating the ware, a mold shiftable with 55 respect to said ware retaining means, and laterally operable means for giving the ware the shape of the mold.

3. A glass shaping machine comprising, in combination, ware retaining means, means for heating a desired portion of the ware, a shaping block, means for alternately bringing the heating means and shaping block into operating position, and means for imparting the configuration of the shaping block 65 to the heated portion of the ware.

4. In a glass shaping machine comprising, in combination, ware retaining means, means for heating a desired portion of the ware, a mold, a wiper, and means for alternately bringing the heating means and the mold into operative relation with the ware for imparting the shape of the mold to the heated portion of the ware.

5. A glass shaping machine comprising, in combination, ware retaining means, means for heating a desired portion of the ware, a mold, means for alternately bringing the heating means and mold into operative position, and laterally operable means for imparting the shape of the mold to the heated portion of the ware.

6. A glass shaping machine, comprising a chuck for holding the ware, means for heating any desired portion of the upper part of the ware, a mold, and a laterally operable shaping member for wiping the heated portion of the ware into the shape of the mold.

7. A beaker lipper machine, comprising a chuck for holding the beaker, means for heating any desired portion of the upper part of the beaker, a mold, and a laterally operable shaping member for wiping the heated portion of the beaker into the shape of the mold.

8. A shaping machine for glass articles comprising a holding device for the article to be worked, movable heating burners, movable shaping devices, said shaping devices comprising a shiftable mold and a laterally movable wiper and a common means for controlling the burners and the two said shaping devices.

9. A glass shaping machine comprising, in combination, ware retaining means, means for heating the ware, a mold shiftable vertically with respect to the ware retaining means and laterally operable means within the shiftable mold and above the ware retaining means for giving the ware the shape of the mold.

In testimony whereof we hereunto affix our signatures.
